UNITED STATES PATENT OFFICE.

GUSTAVOS HEIDEL, OF ST. LOUIS, MISSOURI.

CAR-COUPING.

SPECIFICATION forming part of Letters Patent No. 269,668, dated December 26, 1882.

Application filed October 18, 1882. (No model.)

To all whom it may concern:

Be it known that I, GUSTAVOS HEIDEL, of the city of St. Louis, in the State of Missouri, have invented a certain new and useful Improvement in Car-Couplings, of which the following is a full, clear, and exact description, reference being had to the accompanying drawings, forming part of this specification.

My invention consists in providing the draw-head with a device for lifting the link into position for coupling; also, in combination therewith of a device for lifting the coupling-pin.

Figure 1 is a perspective view, illustrating my invention, showing the lifter and the coupling-pin in their lower position. Fig. 2 is an end view, showing the parts in same position. Fig. 3 is a side view, showing the parts in position for coupling. Fig. 4 is a detail perspective of part of operating bar and arm. Fig. 5 is a detail front view of the cross-pin upon the lever by which the coupling-pin is elevated.

A is the cross-bar of the car-body from which the draw-head B or B' is suspended. The draw-head may be of the usual form. In fact, my device is intended for attachment to cars having ordinary draw-heads thereon and working with a customary link and pin.

C is a hanger-frame secured to the cross bar or timber A, and forming a stirrup, through which passes the lifting-lever D and by which the lever has fulcrum-support.

E is a stirrup-formed guide, through which a lever D passes. The lifting-lever D has a strap, D', extending beneath the fulcrum-hanger C, the strap being of sufficient length to allow considerable endwise movement in the lever, the fulcrum passing along the slot D² as the lever moves backward and forward. The outer end of the lever is turned upward and forked at D³, or has a recess, D⁴, to receive and hold the link when the cars are approaching for coupling, as seen in Fig. 3.

F is a rod extending from side to side of the car-body and turning in bearings G, and provided at each end with a handle, H, by which it is turned.

I is an arm fixed to the middle of the rod and having downturned fingers i resting upon the lever D at the rear of the fulcrum, so that when the rod is turned into the position shown

in the draw-head B' in Fig. 1 the inner end of the lever is depressed and the outer end raised to hold up the entering link L, so that it will be properly presented to the mouth M of the draw-head. As the cars approach and the draw-heads come together the levers D are pushed backward into the position shown in dotted lines in Fig. 3, the salient parts of the draw-heads coming into direct contact, when the fore end of the lever is allowed to drop to its lower position, as shown in Figs. 1 and 2 and in Fig. 3, with the draw-head B. When the rod F is in position of rest, as seen in Figs. 1 and 2, and at B, Fig. 3, the rear end of the lever D is in contact with the bottom of the draw-head, and the inclination of the lever causes it to slide outward ready for use in coupling.

K is a bracket attached to the bar A, forming the fulcrum-bearing of the lever N, that passes through the bracket. The outer end of the lever N is connected to the upper end of the coupling-pin P by a link or hook, O, the pin having an eye at the upper end to enable this connection. The inner end of the lever N has a cross-bar, Q, whose ends are circumferentially grooved for the reception of the ends of a stirrup-link, R, whose lower horizontal part passes through the eye at the end of the finger i' extending from the arm I upon the rod F. The construction is such that when the rod F is turned into the position shown in Fig. 3 in connection with the draw-head B' the link of the approaching draw-head B is raised into coupling position, and at the same time the pin P of the draw-head B' is raised to allow the entrance of the link.

Attention is called to the fact that the lifting-lever upon the head carrying the link can be used to support the outer end of the link, for, as the point of lever-support beneath the link is beyond its center of gravity, the link will rest in coupling position even when the pin P is drawn up; but in this case the pin of the other draw-head must be raised or removed.

I claim—

1. The combination of sliding, lifting, and tilting lever D, transverse rock-bar F, arm I for tilting the lever secured to said bar, and suitable support C for the lever, as set forth.

2. The combination of tilting-lever D, suitable support C, rock-shaft F, arm I, secured thereto, and stirrup E, as set forth.
3. The combination of rock-shaft F, arm I, suitable support K, pin P, lever N, cross-bar Q, and link R, connecting the arm to the cross-bar, as set forth.
4. The combination, with the draw-head of

a railway-car, of the link-lifting lever D, rod F, with arm I, link R, lever N, and pin P, substantially as and for the purpose set forth.

GUSTAVOS HEIDEL.
